UNITED STATES PATENT OFFICE.

ALBERT J. LOEPSINGER, OF EDGEWOOD, RHODE ISLAND, ASSIGNOR TO GENERAL FIRE EXTINGUISHER COMPANY, OF PROVIDENCE, RHODE ISLAND, A CORPORATION OF NEW YORK.

AUTOMATIC SPRINKLER.

1,290,602.

Specification of Letters Patent.

Patented Jan. 7, 1919.

Application filed March 30, 1918. Serial No. 225,748.

To all whom it may concern:

Be it known that I, ALBERT J. LOEPSINGER, citizen of the United States, residing at Edgewood, in the county of Providence and 5 State of Rhode Island, have invented certain new and useful Improvements in Automatic Sprinklers, of which the following is a specification.

My invention relates to automatic sprinklers of the type in which the sprinkler is normally held closed by means of a frangible vessel nearly filled with a liquid and is permitted to open, when sufficiently heated, by the fracturing of the vessel resulting from 15 the expansion of the contained liquid.

In order to be practical, a sprinkler of this type should be so constructed that when the frangible vessel bursts it will be shattered to such an extent that no part of it can 20 remain as an obstruction to interfere with the opening of the sprinkler, and as one way of accomplishing this result it has been proposed to employ a liquid which is charged with gas before the vessel is sealed, in which 25 case the increased tendency of the gas to escape from the liquid when raised to the fracturing temperature is relied on to develop a sufficient shattering pressure. Such sprinklers, however, are open to the objection 30 that their operating temperature is rendered uncertain by reason of the tendency of the gas to escape from the liquid prior to or during the sealing of the vessel, the result of which is that changes in the final volume 35 of the liquid or in the thermal coefficient of expansion, or both, are produced by partial loss of the gaseous contents of the liquid.

In a sprinkler embodying the present invention the objection above referred to is 40 overcome by the employment of a frangible vessel containing a gas-free liquid and a gas which is soluble in the liquid only sparingly, if at all, at atmospheric pressure. The terms "gas-free" and "sparingly soluble," as used 45 above, are intended to mean that the amount of gas contained in the liquid when introduced into the vessel, or absorbed by the liquid before the vessel is sealed, is negligible so far as the operation of the sprinkler is 50 concerned. Since the liquid is gas-free both prior to and at the time of sealing the vessel its coefficient of expansion does not change during sealing and a predetermined definite quantity of the liquid and the gas can be

sealed in the vessel by known methods, so 55 that all factors affecting the operation of the vessel are controlled. Substantial accuracy in respect to operation at a predetermined temperature is thus secured in the case of a single sprinkler, and this results in uniformity of operation in the case of a quantity of the sprinklers, which are essential prerequisites to the practical use of sprinklers of this type. When the sprinkler is heated the 60 gas which fills the expansion space in the vessel is forced into solution in the liquid as the latter expands and is suddenly released as soon as the vessel is fractured at the operating temperature, and I have found that 65 although the volume of gas is small compared with the volume of the liquid itself, its explosive effect when released is nevertheless sufficient to produce the necessary shattering effect on the vessel when fractured.

A form of sprinkler in which my invention 70 may be embodied is illustrated in the accompanying drawings, in which the figure shows the sprinkler in vertical section.

The sprinkler illustrated comprises a body portion 2, a yoke 3 screwed at one end into 75 the body portion 2, a resilient valve seat 4 clamped between the yoke and body portion and having a central perforation, a valve 5 resting on the valve seat 4 and normally closing the perforation therein, and a deflector 6 carried by the free end of the yoke, all of 80 the parts above mentioned being of familiar construction. In addition, the sprinkler includes a ring 7, preferably cast integral with 85 the yoke 3, a cap-piece 8 resting on and centered by the valve 5, and a frangible vessel 90 consisting of a glass bulb 9 interposed between the cap-piece 8 and the ring 7 and serving as a strut to hold the valve 5 against its seat. The neck 10 of the bulb projects 95 upward beyond the ring 7 and is received within a space left in the upper end of the yoke 3, whereby it is protected from accidental breakage, and the rounded bottom of the bulb is received within and kept in position by a concavity formed in the top of the cap-piece 8 and conforming to the contour 100 of the bulb, the parts being so proportioned that when they are assembled and the yoke is screwed into the body portion to clamp the valve seat 4 in place the latter is flexed 105 slightly by the valve 5 and held tightly against the valve by its own elasticity.

The bulb is prepared by first completely filling it with the liquid employed and then heating it and its contents to a temperature, determined by trial, which is less than the intended operating temperature but bears a definite relation to it, depending upon the elasticity and coefficient of thermal expansion of the material of which the bulb is made. This preliminary heating causes the liquid to expand and overflow, leaving in the bulb the proper amount of the liquid to fracture it when sealed and subsequently heated to the operating temperature. The bulb is then cooled to normal temperature, or below, whereupon the contained liquid contracts and leaves an expansion space above it, and during such contraction the gas with which the expansion space is to be filled is permitted to pass freely into the bulb. The preparation of the bulb, the neck of which preferably has a capillary bore, is completed by sealing the neck in the usual way, and the bulb is then combined with the other parts of the sprinkler as already explained.

The liquid which I prefer to use in the bulb is carbon tetrachlorid, which is non-inflammable and chemically stable and does not freeze in cold weather. It also has a boiling point at atmospheric pressure which is higher than the temperature at which most sprinklers are designed to operate, and this is an advantage for the reason that if the fracturing temperature of the bulb is below the boiling point of the liquid there is no danger of loss of liquid by vaporization during the preliminary heating process above described. Carbon tetrachlorid also has a high coefficient of thermal expansion, so that after it has expanded sufficiently to fill the bulb completely it requires but a slight additional increment of heat to produce fracture, which contributes to the accuracy of the sprinkler as regards its operation at a predetermined temperature. A further result of its high coefficient of expansion is that its contraction in volume is relatively great when cooled after the preliminary filling operation, and hence the gas-filled expansion space has a relatively large volume and the shattering action is correspondingly increased. The gas with which the expansion space is filled preferably consists of air, since air is practically insoluble in liquids at atmospheric pressure and its use simplifies the process of preparing the bulb by enabling the preliminary heating and cooling to be carried on in the open air.

Various liquids and gases other than carbon tetrachlorid and air may be employed in the construction of sprinklers embodying my invention, and the operating temperature of the sprinkler need not necessarily be lower than the boiling point of the liquid at atmospheric pressure, but if the boiling point of the liquid is below the temperature

reached during the preliminary heating of the bulb this heating should be done while the liquid is subjected to a pressure sufficient to prevent loss by vaporization, and preferably in an atmosphere of the gas with which the expansion space is to be filled. In such case, when the sprinkler operates the shattering effect may be increased by partial vaporization of the liquid itself, which will supplement the effect produced by the sudden release of the gas forced into solution in the liquid.

While my invention is particularly adapted and intended for use in automatic sprinklers, it will be evident that the above-described frangible vessel and its contents, in which the novelty of my invention primarily resides, constitute an article of manufacture which can be used as a thermostatic release in a variety of devices intended to operate at a predetermined temperature.

I claim:

1. An automatic sprinkler comprising, as a means for normally holding the sprinkler closed, a frangible vessel which is nearly filled with a gas-free liquid and in which the remaining space is filled with a gas which is sparingly soluble in the liquid at atmospheric pressure.

2. An automatic sprinkler comprising, as a means for normally holding the sprinkler closed, a frangible vessel nearly filled with a liquid which has a boiling point higher than the intended operating temperature of the sprinkler, the remaining space within the vessel being filled with a gas which is sparingly soluble in the liquid at atmospheric pressure.

3. An automatic sprinkler comprising, as a means for normally holding the sprinkler closed, a frangible vessel nearly filled with a liquid which has a high coefficient of thermal expansion, the remaining space within the vessel being filled with a gas which is sparingly soluble in the liquid at atmospheric pressure.

4. An automatic sprinkler comprising, as a means for normally holding the sprinkler closed, a frangible vessel nearly filled with carbon tetrachlorid, the remaining space within the vessel being filled with a gas which is sparingly soluble in the carbon tetrachlorid at atmospheric pressure.

5. An automatic sprinkler comprising, as a means for normally holding the sprinkler closed, a frangible vessel nearly filled with carbon tetrachlorid, the remaining space within the vessel being filled with air.

6. An article of manufacture consisting of a frangible vessel which is nearly filled with a gas-free liquid and in which the remaining space is filled with a gas which is sparingly soluble in the liquid at atmospheric pressure.

7. An article of manufacture consisting of a frangible vessel nearly filled with a liquid

which has a high co-efficient of thermal expansion, the remaining space within the vessel being filled with a gas which is sparingly soluble in the liquid at atmospheric pressure.

5 8. An article of manufacture consisting of a frangible vessel nearly filled with carbon tetrachlorid, the remaining space within the

vessel being filled with a gas which is sparingly soluble in the carbon tetrachlorid at atmospheric pressure.

10

Signed at Providence, Rhode Island, this 28th day of March, 1918.

ALBERT J. LOEPSINGER.
